COMBINED AIR PUMP AND ADAPTER FOR VEHICLE RADIATOR TESTING

Wilbur B. Hughes, Detroit, Mich.

Application October 1, 1954, Serial No. 32,502

Term of patent 7 years

(Cl. D65—1)

Fig. 5~

Fig. 3~

Fig. 4~

Fig. 1 is a top plan view of a combined air pump and adapter for vehicle radiator testing, showing my new design.

Fig. 2 is a view of the same in side elevation.
 Fig. 3 is a front end view of the same.
 Fig. 4 is a corresponding rear end view.
 Fig. 5 is a cross sectional view of the pump, taken on the line 5—5 of Fig. 2.

I claim:

The ornamental design for an air pump and adapter, as shown.
